UNITED STATES PATENT OFFICE

96,649

DESIGN FOR AN ASH RECEPTACLE

Carl E. Carlson, Chicago, Ill., assignor to Precision Metal Workers, Chicago, Ill., a corporation of Illinois

Application June 20, 1935, Serial No. 57,346

Term of patent 7 years

To all whom it may concern:

Be it known that I, Carl E. Carlson, a citizen of the United States, a resident of Chicago, in the county of Cook and State of Illinois, have invented a new, original, and ornamental Design for Ash Receptacles, of which the following is a specification, reference being had to the accompanying drawing, forming part thereof.

Figure 1 is a perspective view of the ash receptacle; and

Figure 2 is a similar view after the receptacle has been turned on its vertical axis through an angle of approximately 90°.

I claim:

The ornamental design for an ash receptacle, as shown.

CARL E. CARLSON.
